US0D1102576S

(12) **United States Design Patent** (10) **Patent No.:** **US D1,102,576 S**
(45) **Date of Patent:** **** Nov. 18, 2025**

(54) **NECK FAN**

(71) Applicant: **Tianxi Liu**, Yuanjiang (CN)

(72) Inventor: **Tianxi Liu**, Yuanjiang (CN)

(**) Term: **15 Years**

(21) Appl. No.: **29/950,762**

(22) Filed: **Jul. 4, 2024**

(51) LOC (15) Cl. **23-04**

(52) U.S. Cl. **USPC D23/380**

(58) **Field of Classification Search**

USPC D23/332, 333, 351, 355, 370, 380
CPC F24F 5/00; F24F 13/32; F24F 11/52; F24F
2221/38; F24F 2221/12; F24F 2120/00

CLAIM

The ornamental design for a neck fan, as shown and described.

DESCRIPTION

FIG. 1 is a front perspective view of a neck fan, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines and de-emphasized areas within broken lines depict portions of the neck fan that form no part of the claimed design.

1 Claim, 8 Drawing Sheets
